[57] CLAIM

The ornamental design for a can, as shown and de-
scribed.

DESCRIPTION

FIG. 1 is a perspective view of a can illustrating our
new design;

FIG. 2 is a side elevational view thereof;

FIG. 3 is a top plan view thereof; and

FIG. 4 is a bottom plan view thereof;

FIG. 5 is a rear view shown on a reduced scale of the
container in FIG. 2.
